Primary Examiner — Janice Hallmark*Assistant Examiner* — Rebecca Tsehay(74) Attorney, Agent, or Firm — Millen, White, Zelano & Branigan, P.C.; William Nixon(57) CLAIM

The ornamental design for an applicator, as shown and described.

DESCRIPTION

FIG. 1 illustrates a front perspective view of the applicator having the claimed design;

FIG. 2 illustrates a side elevational view thereof;

FIG. 3 illustrates a top plan view thereof;

FIG. 4 illustrates a bottom plan view thereof; and,

FIG. 5 illustrates an exploded view of the applicator having the claimed design.

The broken lines shown throughout the views depict unclaimed portions of the design and form no part of the claimed design.
